UNITED STATES PATENT OFFICE.

WILLIAM F. BLAKE, OF HARVEY, ILLINOIS, ASSIGNOR, BY MESNE ASSIGNMENTS, TO PARAGON MFG. CO., OF CHICAGO, ILLINOIS, A CORPORATION OF ILLINOIS.

WASHING-MACHINE.

No. 900,268.

Specification of Letters Patent.

Patented Oct. 6, 1908.

Application filed December 24, 1906. Serial No. 349,261.

To all whom it may concern:

Be it known that I, WILLIAM F. BLAKE, a citizen of the United States, residing at Harvey, county of Cook, State of Illinois, have invented a certain new and useful Improvement in Washing-Machines, and declare the following to be a full, clear, and exact description of the same, such as will enable others skilled in the art to which it pertains 10 to make and use the same, reference being had to the accompanying drawings, which form a part of this specification.

My invention relates in general to washing machines and particularly to that type of 15 washing machines in which a perforated cylinder containing articles to be washed, is rotatably mounted within a casing containing water.

An object of my invention is to provide 20 means for readily disengaging the driving pinion from the gear wheel on the cylinder to permit the removal of the cylinder from the casing, and which will also lock the cylinder against rotation when it is desired to remove 25 the articles therefrom.

A further object is to provide improved 30 means for securing the circular wall of the cylinder to the end walls, which will also serve as handles to facilitate the lifting of the cylinder from the casing.

A further object is to prevent leakage of 35 water from the casing around the bearing plate of the driving shaft.

A further object is to protect the exposed 40 metal in the perforations of the galvanized cylinder so that the clothes will not be injured by rust.

A still further object of my invention is to 45 provide a washing machine which will be simple in construction, inexpensive in manufacture, and efficient in use.

My invention will be more fully described 50 hereinafter with reference to the accompanying drawings in which the same is illustrated as embodied in a convenient and practical form and in which

Figure 1 is a plan view, the cover of the 55 casing being open; Fig. 2 a transverse sectional view on line 2—2 Fig. 1, the cover of the casing being closed; Fig. 3 an enlarged detail sectional view on line 3—3 Fig. 1; Fig. 4 a transverse sectional view on line 4—4 Fig. 1; Fig. 5 a detail sectional view on line 5—5 Fig. 4; Fig. 6 an edge elevational view 60 of the bearing plate detached from the cas-

ing; Fig. 7 an elevational view of the side of the bearing plate which engages the end wall of the casing; Fig. 8 an enlarged elevational view of the top portion of one of the end walls of the cylinder; Fig. 9 a sectional view on line 9—9 Fig. 8.

The same reference characters are used to designate the same parts in the several figures of the drawings.

Reference characters A and A² indicate 65 the end walls of the casing which are united by side walls A³ and A⁴.

A indicates the cylindrical bottom wall of the casing which is preferably made of sheet metal.

a, a designate the legs for supporting the 70 casing, which are preferably made of angle iron and are extended upwardly to the top of the casing and serve as corner brackets for strengthening the connections between the 75 walls of the casing.

Reference letter B designates the cover of the 80 casing which is preferably made of sheet metal and is united at one edge to a hinge b extending the entire length of the side wall A⁴ of the casing. The hinge b is provided with a downwardly extending flange b' overlapping the inner surface of the wall A⁴, thereby adding strength to the hinge and also preventing a sharp edge being presented 85 by the hinge to cut or injure the hands of the operator. Handles A⁵ and A⁶ are secured on the outer surfaces of the end walls A' and A² of the casing to permit the machine to be moved.

C designates a perforated cylinder rotatably mounted within the casing and adapted 90 to contain articles, such as clothes, to be washed. The cylinder is preferably made of galvanized sheet metal, and in order to prevent the ungalvanized portion within the 95 perforations rusting the clothes, brass eyelets such as indicated at c are inserted in the perforations and flanged, as clearly shown in Fig. 2. The walls within the perforations are 100 consequently covered so that no rust will be transferred therefrom to the clothes.

C' designates the cover of the cylinder 105 which is hinged thereto at one edge and at its other edge is provided with a latch for retaining the same closed. Such latch is preferably of the form shown in Fig. 3 and comprises a bar E mounted to slide upon the cover by means of a knob e, and having two key-hole slots e', e' therein adapted to sur- 110

round studs e^1 , e^2 projecting upwardly from the adjacent edge of the cylinder. It is obvious that by sliding the bar E into position for the larger portions of the key-holes to register with the studs the cover C' may be swung upwardly, while by sliding the bar in an opposite direction the restricted portions of the key-holes will engage beneath the heads of the studs and securely lock the cover to the cylinder.

Each of the end walls C' of the cylinder is provided with a segmental plate F located immediately below the cover C' of the cylinder. Such plate is provided on its outer surface with a depression f which serves as a handle to facilitate the cylinder being lifted out of the casing. Each plate F is provided at its ends with eyes f', and f'', through which extend the ends of a wire hoop G which is secured to the adjacent end of the cylindrical wall, preferably by having the edge of the cylindrical wall bent around the hoop. The ends of the hoop G are reversely screw-threaded and engage within screw-threaded openings in a turn buckle g, such turn buckle lying within the depression f of the plate F. It is obvious that by rotating the turn buckle g the ends of the hoop are drawn together and the adjacent portion of the cylindrical wall is thereby drawn tightly around the end wall of the cylinder. The drawing of the cylindrical wall against the edges of the end walls produces a hollow cylinder with tight joints at the ends and by reason of the engagement of the hoops with the segmental plates on the end walls axial displacement of these walls is prevented and a secure and permanent union between the various parts is obtained.

C' designate longitudinal strips secured to the inner surface of the cylinder which when the cylinder is revolved serve to lift the clothes and thereby subject them thoroughly to the water.

Trunnions d' and d² project from the end walls of the cylinder and are journaled in brackets D' and D² secured to the inner surfaces of the end walls of the casing. A plate D is formed integrally with the bracket D' and is provided with a tubular bearing D³ in which is journaled a stub shaft H extending through the end wall A' of the casing. A wheel h is fixed upon the outer end of the shaft H and has thereon a crank handle for revolving the shaft. A pinion h' is fixed upon the inner end of the shaft H and is adapted to mesh with a gear wheel H' fixed to the cylinder concentrically around the trunnion d'. A lever K is fulcrumed upon the inner surface of the plate D and is provided with a flange k adapted to engage the pinion h' and retain the same in mesh with the gear wheel H'. The lever K is also provided with a laterally extending lug k' having a recess therein adapted to engage one of the teeth of the pinion h' and thereby lock the

same against rotation. A series of notches l', l², l³ are formed in a flange at the upper end of the plate D to be engaged by the lever K and thereby lock the same in its several positions, the upper portion of the lever being sufficiently resilient to permit it to be deflected into and out of engagement with the notches. A circular recess d is provided in the plate D to receive the pinion h' when the shaft H is drawn outwardly to remove the pinion from engagement with the gear wheel preparatory to lifting the cylinder out of the casing. A collar D⁵ closely surrounds the tubular bearing d³ on the outside of the end wall of the casing to prevent leakage of water between the casing and plate D.

The plate D is provided with a vertical channel in which is guided a bar M to the offset lower end of which is secured a chain M'. The lower end of the chain is secured to the stem of a valve located within a valve casing N secured to the bottom wall A of the casing, such casing being provided with an outlet n and an inlet leading thereto above the valve. The bar M is provided with a shoulder m near the upper end thereof which is adapted to overlie the adjacent edge of the plate to retain the bar in elevated position and thereby hold the valve away from its seat to permit the water to be discharged from the casing.

O designates a soap box located within the casing adjacent the top of the wall A³. The box O is in the form of an angular piece of metal as shown in the drawings and is hinged at the lower edge by means of a rod o engaging a pair of brackets O' and O² fixed to the wall A³. Each of the brackets is provided with a shoulder upon which the bottom wall of the soap box normally rests, as shown in Fig. 2. When it is desired to remove the cylinder from the casing the soap box O is swung upwardly so that the inner surface of its bottom wall lies close to the upper portion of the adjacent wall of the casing.

P' and P² indicate shields in the form of clips which straddle the top of the wall A³ of the casing and may be adjusted thereon so as to occupy positions corresponding to the clamps of a clothes wringer. The clamps of the clothes wringer surround and engage the shields P' and P², the shields therefore serving to afford a secure support for the clothes wringer and also to protect the wall of the casing from injury by the clamps of the wringer.

The operation of my improved washing machine is as follows: When the lever K is in the position shown in Figs. 1 and 4 the cylinder is held stationary within the casing so that its cover may be elevated and clothes or other articles may then be inserted in or removed from the cylinder. When it is desired to rotate the cylinder to wash the articles the lever K is adjusted to engage the

notch l' thereby disengaging the lug k' thereon from the pinion h' , but retaining the lug k in engagement with the pinion so that the same will be kept in mesh with the gear wheel H' . The hand wheel h is then rotated thereby rotating the shaft H , the pinion h' fixed thereon, the gear wheel H' , and the cylinder to which the gear wheel is fixed. When it is desired to remove the cylinder 10 from the casing the lever K is engaged with the notch l' thereby removing the lug k thereon from between the pinion and plate D , so that the shaft H may be drawn outwardly and the pinion moved out of mesh 15 with the gear wheel, such movement of the pinion being permitted by the recess d in the plate D which receives the pinion.

The functions and operations of the various other improved features of my invention have been sufficiently described in connection with the description of their constructions so that further detailed description is unnecessary.

From the foregoing description it will be observed that I have invented a washing machine embodying a number of improvements whereby the machine is rendered more satisfactory in operation and more convenient in use.

Having now fully described my invention, what I claim as new and desire to secure by Letters Patent is:

1. In a washing machine, the combination with a casing, of a cylinder rotatably supported within said casing, a gear wheel fixed to said cylinder, a pinion meshing with said gear wheel, an axially movable shaft on which said pinion is fixed, and adjustable means which retains said pinion in mesh with 35 said gear wheel, or permits said pinion to be disengaged from said gear wheel to allow the removal of the cylinder from the casing or locks said pinion against rotation when engaged with said gear wheel to retain 40 said cylinder immovable while articles are being inserted therein or removed therefrom.

2. In a washing machine, the combination with a casing, of a cylinder rotatably supported within said casing, a gear wheel fixed 50 to said cylinder, a pinion meshing with said gear wheel, an axially movable shaft on which said pinion is fixed, for disengaging said pinion from said gear wheel to permit the removal of said cylinder from said casing, an oscillatory lever for locking said shaft against axial movement when said pinion is in mesh with said gear wheel, and for locking 55 said pinion against rotation to prevent the rotation of said cylinder while articles are being inserted therein or removed therefrom.

3. In a washing machine, the combination with a casing, of a cylinder rotatably supported within said casing, a gear wheel fixed to said cylinder, a pinion meshing with said 60 gear wheel, an axially movable shaft on

which said pinion is fixed, an oscillatory lever for locking said shaft against or permitting axial movement thereof to engage and disengage said pinion with said gear wheel to permit the cylinder to be removed from or 70 inserted in said casing and for locking said pinion against rotation when meshing with said gear wheel, to retain said cylinder immovable while articles are inserted therein or removed therefrom, and means for retaining 75 said lever in its adjusted positions.

4. In a washing machine, the combination with a casing, of a cylinder rotatably supported within said casing, a gear wheel fixed to said cylinder, a pinion meshing with said gear wheel, an axially movable shaft on which said pinion is fixed to disengage said pinion from said gear wheel to permit said cylinder to be removed from said casing, an oscillatory lever, a lug on said lever for engaging said pinion to retain the same in mesh with said gear wheel, said lever having a recess to engage a tooth of said pinion to lock 85 the same against rotation and thereby retain such cylinder immovable while articles are 90 inserted in or removed therefrom.

5. In a washing machine, the combination with a casing, of a cylinder rotatably supported within said casing, a gear wheel fixed to said cylinder, a pinion meshing with said 95 gear wheel, an axially movable shaft on which said pinion is fixed to disengage said pinion from said gear wheel to permit the removal of said cylinder from said casing, a plate through which said shaft extends, secured to the inner surface of an end wall of said casing, a lever pivotally mounted upon said plate, a lug on said lever for controlling the axial movement of said shaft, and means on said lever for locking said pinion against 100 rotation when meshing with said gear wheel and thereby retain said cylinder immovable to permit articles to be inserted therein or removed therefrom.

6. In a washing machine, a cylinder made 110 up of a cylindrical wall and end walls, hoops secured at opposite ends of said cylindrical wall adjacent the end walls, means located adjacent each end wall for drawing the ends of the corresponding hoop together, and 115 means on each end wall engaging with the adjacent hoop to prevent axial displacement of the end wall.

7. In a washing machine, a perforated sheet iron cylinder having arranged within 120 the perforations eyelets to prevent the transmission of rust from the edges of the cylinder around the perforations to articles contained within the cylinder, said eyelets being provided at opposite ends with annular flanges 125 which overlap the cylinder adjacent the perforations.

8. A cylinder for a washing machine, comprising a cylindrical wall, a pair of end walls, 130 hoops carried upon the ends of said cylinder

- drical wall, recessed plates secured to the inner surfaces of said end walls, and turn buckles connecting the ends of said hoops and extending into the recesses in said plates.
5. 9. A cylinder for a washing machine comprising a sheet metal cylindrical wall, end walls, hoops secured to the ends of said cylindrical wall, said end walls having recesses in their outer surfaces, and means extending 10 into said recesses for securing the ends of the hoops together.
10. A washing machine cylinder comprising a sheet metal cylindrical wall, end walls having recesses in their outer surfaces, hoops 15 about which the ends of said cylindrical wall are bent, and means extending into said recesses for connecting together the ends of said hoops.
11. In a washing machine, the combination 20 with a frame, of a casing supported by said frame, a cylinder revolvably supported by

said frame within said casing, a plate supported upon the inside of one wall of the frame adjacent one end of the cylinder, a stub shaft slidably mounted on said plate, complementary gears between said stub shaft and said cylinder, said plate having a recess therein to permit the gear on the stub shaft to be carried out of engagement with the gear on the cylinder, a lever pivoted on 25 said plate and provided with means for locking the gear on the stub shaft against rotation and with means for locking it in its operative relation with respect to the gear on the cylinder.

In testimony whereof, I sign this specification in the presence of two witnesses.

WILLIAM F. BLAKE.
